UNITED STATES PATENT OFFICE.

EDWARD T. BURROWES, OF PORTLAND, MAINE.

KEY-RETAINER.

SPECIFICATION forming part of Letters Patent No. 761,059, dated May 31, 1904.

Application filed March 30, 1903. Serial No. 150,235. (No model.)

To all whom it may concern:

Be it known that I, EDWARD T. BURROWES, a citizen of the United States, residing at Portland, in the county of Cumberland and State 5 of Maine, have invented certain new and useful Improvements in Key-Retainers, of which the following is a specification, reference being had therein to the accompanying drawings.

This invention relates to a novel key-retainer, and has for its object the provision of a device for preventing accidental withdrawal and dropping of a key from its keyhole. The invention also contemplates the provision of a construction which will to a limited extent 15 resist the turning of a key from the outside of a door, whereby the same is in the nature of a safety device against intruders.

Novel details of the construction and arrangement of the several parts of the device 20 will be apparent from the detailed description hereinafter when read in connection with the accompanying drawings, forming part hereof. Several of the preferable embodiments of the invention are illustrated in the drawings for 25 the purpose of facilitating a clear understanding of the invention. It is, however, to be understood that it is not intended that the invention be limited to the details of any such embodiments disclosed except in so far as any 30 features of the same may be specifically included in the appended claims, because minor changes and alterations may be made without in the least departing from the spirit of the invention.

35 In the drawings, Figure 1 is a perspective view of a portion of a door, illustrating one form of the device as applied thereto, the key shown in this instance being of the flat-shank variety. Fig. 2 is an elevation of Fig. 1. Fig. 3 is a sectional view on the line xx of Fig. 2 looking in the direction of the arrow. Fig. 4 is a front elevation of a slightly-modified form of device, the knob-shank and key-shank being shown in section. Fig. 5 is an 40 edge view of Fig. 4, and Figs. 6, 7, and 8 are fragmentary views illustrating various details of construction.

Referring more particularly to the drawings, wherein like reference characters designate 45 corresponding parts in the several views,

A designates the shank of a door-knob, which is of the ordinary type, around which fits a cover or finishing plate or ring B, said plate in turn being secured to the face of the door.

C is a split wire ring or loop adapted to be 55 slipped over the knob-shank and hung upon a headed pin D, which will hold the ring in place and prevent movement thereof longitudinally of said shank. Engaging the lower portion of the ring or loop is the upper end 60 of a coiled spring E, which is suspended from said ring and is at its opposite end formed into a hook e, engaging an eye e' of a key-engaging device F.

The device F referred to is designed more 65 particularly for use in connection with keys having a flat shank, as indicated at G, Fig. 3, to which end it is formed with a normally horizontally disposed flatspring-loop f, adapted to embrace the key-shank, and a laterally-projecting handpiece f' for disengaging the 70 loop from the key, said loop being split at any desired point, or the same may be of an endless flexible material adapted to be forced over the end of the key. The eye e' is formed 75 centrally of the upper bar of the flat loop f, so as to retain the latter in its horizontal position. By this arrangement when the key is turned into locked position its shank will occupy a horizontal plane and be firmly grasped 80 by the spring-loop, so that the turning of the key by instruments from the outside of the door will be to a limited extent resisted, the constant tension of the spring E aiding materially in this respect. The elasticity of the 85 spring or its equivalent connection enables the ready application of the device to doors wherein in the knob and key are at different distances apart. It will be further appreciated that while the loop f normally retains the key-shank in a 90 horizontal plane said loop, however, has sufficient resiliency, owing to the character of the material from which it is formed, to give enough to permit the forced turning of the key 95 therein by the usual manipulation of the key from the inside of the door. Also in the event of the key being turned, together with the device F, and the key left with its bit end in a vertical plane and in registration with the keyhole the device will be restored to its normal posi-

tion by the spring E, incidentally shifting the key a quarter-turn to destroy such registration.

In the embodiment of Figs. 4 and 5, H designates the shank of a door-knob, which is preferably circular in cross-section, as is ordinarily the case, and adapted to engage therewith, and capable of ready attachment to and detachment from the same is a split ring J, formed of spring metal and terminating at one end in a downwardly-extending hook j. To this hook the hooked end k of a coil-spring K is secured, the opposite end of said spring being also hooked, as at k', and connecting to the hooked end e of a split spring-ring L, adapted to receive the shank of a key and loosely engage the same, whereby the key may readily rotate, the shank of the key in the present instance being rounded in cross-section. By this arrangement it will be seen that the device is of a very simple character, is readily attached to a door-knob and key, and while permitting free rotation of the key will effectually retain the same in place. To facilitate detachment of the ring J from the key, a handpiece M is connected thereto, said handpiece depending from said ring in such manner as to afford no appreciable obstruction or objectionable appearance, but within easy access.

In the form shown in Fig. 6 the plate or ring B' is provided with a projection b, back of which the ring C may be fitted instead of over the headed pin D, as in the form first above described.

Fig. 7 discloses another form, in which both the headed pin D and the lug b of the preceding forms are dispensed with. In this instance the upper end of the spring E is secured directly to the plate or ring B² through the medium of a screw-eye b², depending from said plate or ring.

Fig. 8 shows another manner of fashioning the key-engaging loop. Its formation is obvious.

Having thus described the invention, what is claimed as new, and desired to be secured by Letters Patent, is—

1. Key-retaining instrumentalities including a spring, a ring secured to one end of the spring, and a connecting device secured to the other end thereof, in combination with means for preventing movement of the retainer longitudinally of the key.

2. A key-retainer comprising a relatively flat loop adapted to embrace the shank of a key and turn therewith, and an elastic device for causing said loop to normally assume an approximately horizontal position.

3. A key-retainer comprising a relatively flat loop adapted to embrace the shank of a key and turn therewith, and means for causing said loop to normally assume an approximately horizontal position.

4. A key-retainer comprising means for se-

curing the same to a key whereby the key may turn without affecting the normal operative relation of the device thereto, and means for automatically turning the key from a position in registration with a keyhole to a position out of registration therewith.

5. A key-retainer comprising a ring, a relatively flat loop adapted to embrace the shank of the key, and a flexible connection between said ring and loop. 75

6. A key-retainer comprising a ring, a relatively flat loop adapted to embrace the shank of the key, and an elastic connection between said ring and loop.

7. A key-retainer comprising a flexible 80 member, and a relatively flat loop carried thereby adapted to embrace the shank of the key.

8. A key-retainer comprising a relatively flat loop adapted to embrace the shank of a key 85 and turn therewith, and means for returning said loop to a normal position when the key is turned.

9. A key-retainer comprising a relatively flat loop adapted to embrace the shank of a key 90 and turn therewith, and an elastic device for returning said loop to a normal position, when the key is turned.

10. A key-retainer comprising separated loops one of said loops being substantially continuous and split, a connecting device therebetween, and a handpiece carried by the split loop. 95

11. A key-retainer comprising separated loops one of said loops being substantially continuous and split, an elastic connecting device therebetween, and a handpiece carried by the split loop. 100

12. A key-retainer comprising separated loops, one adapted to engage the key to permit turning of the key without detaching the retainer therefrom, a connecting device therebetween, and a handpiece carried by one of the loops. 105

13. A key-retainer comprising separated loops, one adapted to engage the key to permit turning of the key without detaching the retainer therefrom, an elastic connecting device therebetween, and a handpiece carried by one of the loops. 110

14. A key-retainer comprising means for securing the same to a key whereby the key may turn without affecting the normal operative relation of the device thereto, said means including means for engaging a fixture on the door, means for embracing the stem of the key at a point intermediate its bow and bit, and a flexible connection between said two last-mentioned means. 120

15. A key-retainer comprising means for securing the same to a key whereby the key may turn without affecting the normal operative relation of the device thereto, said means including means for engaging a fixture on the door, means for engaging the key, and an 130

elastic connection between said last two mentioned means.

16. A key-retainer comprising an attaching device, an elastic connecting device secured at one end to said attaching device, and a relatively flat loop secured to the opposite end of said connecting device at a point at approximately the center of the upper edge of said loop.
17. A key-retainer comprising an attaching device, an elastic connecting device secured at one end to said attaching device, and a relatively flat spring-loop secured to the opposite end of said connecting device at a point at approximately the center of the upper edge of the loop.
18. A key-retainer comprising means for securing the same to a key whereby the key may turn without affecting the normal operative relation of the device thereto, said means including separated split loops and a flexible connection therebetween.
19. A key-retainer comprising a relatively flat spring-loop adapted to embrace the shank of a key, a handpiece on said loop projecting outwardly therefrom, and a support device connected to a portion of the loop and movable therewith.
20. A key-retainer comprising means for securing the same to a key whereby the key may turn without affecting the normal operative relation of the device thereto, said means including separated split loops and an elastic connection therebetween.
21. A key-retainer comprising means for securing the same to a key whereby the key may turn without affecting the normal operative relation of the device thereto, said means including a loop adapted to engage a fixture on a door, a flexible connection depending therefrom in approximate vertical alinement therewith, and means on said flexible connec-

tion arranged to embrace the stem of the key at a point intermediate its bow and bit.

22. A key-retainer comprising means for securing the same to a key whereby the key may turn without affecting the normal operative relation of the device thereto, said means including a loop adapted to engage a fixture on a door, and an elastic connection depending therefrom in approximate vertical alinement therewith.

23. A key-retainer comprising an attaching device, an elastic connecting device secured at one end thereto, and a relatively flat loop adapted to embrace the shank of a key having an eye arranged centrally of its upper portion secured to the opposite end of the connecting device.

24. A key-retainer comprising a loop, an attaching device, and elastic means intermediate of and constituting a direct straight connection between said device and loop.

25. A key-retainer comprising an attaching device, a spring constituting a connecting device secured at one end thereto, and a relatively flat loop adapted to embrace the shank of a key having an eye arranged centrally of its upper portion secured to the opposite end of the connecting device, in combination with means for securing the retainer close to the face of a door.

26. A key-retainer comprising a loop, an attaching device, and elastic means intermediate of and constituting a direct straight connection between said device and loop, in combination with means for securing the retainer close to the face of a door.

In testimony whereof I affix my signature in presence of two witnesses.

EDWARD T. BURROWES.
